DOOR LOCK

Robert Buchanan McFarlane, Toronto, Ontario,
Canada

Application October 9, 1937, Serial No. 168,134

9 Claims. (Cl. 292—177)

My invention relates to improvements in door locks for automobiles and the like, and the object of my invention is to provide a lock mechanism wherein the usual protruding door handle is eliminated, and wherein the lock is actuated by a press button embedded in the door and having its outer face substantially flush therewith.

Another object of my invention is to incorporate a lock in such press button, so that by actuation of a key the press button can be locked against inward movement and thus lock the door.

A further object of my invention is to furnish my lock with the usual bolt which protrudes from the edge of the door, and to provide for the spring actuation of such bolt through a plunger member which also protrudes from the edge of the door and which is pushed inwardly into the lock by the door jamb when the door is being closed, such inward movement of the plunger setting a spring mechanism which shoots the bolt when the bolt is registering with its receiving orifice in the door jamb.

A still further object of my invention is to furnish a simple trigger mechanism actuated by the inward movement of the press button on the door, such trigger mechanism releasing the spring mechanism in the lock to retract the bolt.

With the foregoing and other objects in view, as shall hereinafter appear, my invention consists of a door lock constructed and arranged all as hereinafter more particularly described and illustrated in the accompanying drawing, in which:

Figure 1 is a front elevational view of my lock as applied to a fragmentary portion of a steel door. In this view the lock is shown as when the door is open.

Figure 2 is a similar view to Figure 1. In this view the lock is shown as when the door is partially closed, that is, with the plunger engaging the jamb and before the locking bolt is shot.

Figure 3 is a similar view to Figure 1. In this view the door is shown fully closed and the bolt shot.

Figure 4 is a similar view to Figure 1. In this view the press button is shown as having been moved inwardly to permit the bolt to be retracted under a spring mechanism, the lock being in the position wherein the door is ready for opening.

Figure 5 is a horizontal cross-sectional view through the outer edge portions of the automobile door and jamb, showing the lock in the position as illustrated in Figure 3, that is, the door locked.

Figure 6 is a similar view to Figure 5, the lock

being in the position as shown in Figure 4, that is, with the press button moved inwardly.

Figure 7 is a horizontal cross-sectional view through the edge portion of the automobile door showing the upper edge portion of my lock in 5 the locking position, as illustrated in Figure 3.

Figure 8 is a vertical cross-sectional view through the press button, showing the mounting therefor, and the key operated roll-back contained therein.

Figure 9 is a cross-sectional view through the door jamb and illustrating the movable spring actuated lug protruding from the jamb to open the door when the door bolt is retracted, and

Figure 10 is a front elevational view of a fragmentary portion of the door containing the lock and also a fragmentary portion of the door jamb.

Like characters of reference indicate corresponding parts in the different views of the drawing.

My lock mechanism is mounted upon a base plate 1 and this plate is secured against the inner side of the door 2 in any suitable manner. A lock bolt 3 and a plunger 4 alternately protrude through orifices in the edge of the door and slide 25 upon the face of the plate 1. The plunger 4 is formed with a chamfered outer face 5 so that it is readily retractable as such chamfered face engages the door jamb.

The inner end of the plunger 4 is slidably 30 attached to a slide block 6, such slide block being of L-shaped form and provided with a slot 7 through which a pin 8 carried upon the plunger 4 freely projects. The inner end of the plunger 4 is also attached to a rod 9 which extends across 35 the plate 1 and is movable with the plunger. The outer end of the rod 9 is slidably contained within an orifice in the upturned end of a bracket 10 secured to the plate 1. The plunger 4 and rod 9 are resiliently held against inward movement by 40 the provision of a spiral spring 11 carried upon the rod 9 and having one end engaging the upturned portion of the bracket 10 and its other end engaging a collar 12 secured upon the rod 9.

The lock bolt 3 is attached at its inner end to 45 a strip 13 extending across the plate 1. Such strip is formed with a slot 14 and the plate 1 carries a stud 15 which protrudes through the slot to support the strip and to also form part of a locking device for securing the door from the 50 inside, as shall hereinafter appear.

The plunger assembly and the bolt assembly are connected by a lever 16 formed with an orifice 17 intermediately of its length, and through which orifice a rod 18 extends. The rod 18 is con- 55

tained within the vicinity of its ends within a pair of lugs 19 and 20 which protrude upwardly from the face of the plate 1. The lug 20 is formed with a V-shaped edge 21 against which the lever 16 fulcrums. The upper end of the lever 16 is pivoted upon a pin 22 projecting from the strip 13, and the lower end of the lever is formed with an orifice 23 through which the rod 9 extends. The lower end of the lever 16 also rests against a protuberance 24 upon the end of the slide block 6.

A second lever 25 extends between the stationary rod 18 and the movable rod 9. This lever is fulcrumed upon a pivotal pin 26 protruding from the plate 1 and is formed with orifices 27 and 28 in its ends and through which the rods 18 and 9 extend. A pair of spiral springs 61 and 62 are carried upon the rods 18 and 9 respectively and are interposed between the levers 16 and 25.

For controlling the relative movements of the plunger 4 and slide block 6, I form the outer face of the plunger 4 with a transverse slot 29 adapted to receive a stop bar 30 which is pivoted at its lower end between a pair of lugs 31 projecting from the lower face of the plunger 4. When the stop bar 30 is depressed into the slot 29, as illustrated in Figure 6, the slide block 6 can slide across the outer face of the plunger 4 within the limits of its slot 7 and pin 8 protruding thereinto. When the bar 30 is swung partly out of the slot to project above the outer face of the plunger 4, the side of such bar engages the adjacent end of the slide block 6 and thus the slide block and plunger can only move in unison. The upper end of the stop bar 30 is formed into a U-shape 32 and its end portion lies tangentially in respect to the press button assembly.

The press button assembly comprises a cylinder 33 so positioned as to have its outer end contained within a recess 34 in the outer face of the door. The cylinder is formed with a bottom 35 having an orifice 36 in one side thereof, such orifice receiving a stud 37 which projects outwardly from the plate 1 between the plunger 4 and bolt 3. The stud 37 is formed with a diametrical slot 38 extending from its lower end to the vicinity of its top, and the lower end of the cylinder 33 contains a bridging bar 39 extending diametrically across the cylinder and through the outer end of the slot 38 in the stud 37. By this construction the cylinder 33 can be moved in or out upon the stud 37 but cannot be removed therefrom. A spiral spring 40 surrounds the stud 37 and is interposed between the plate 1 and the bottom 35 of the cylinder 33 so that the cylinder is normally retained in the outermost position relatively to the stud, as illustrated in Figure 8.

One end of the bridging bar 39 is utilized to carry a jaw 41 and the recess 43 within the jaw contains the upper end portion of the stop bar 30. It will thus be apparent that when the press button or cylinder 33 is pushed inwardly that as the jaw 41 moves therewith the end of the stop bar 30 will also be depressed, thus moving the lower end of the stop bar into the slot 29 from out of its abutting position against the slide block 6. The upper end of the cylinder 33 contains a lock 44 and from which protrudes a bolt 45 which is contained within the cylinder and movable from the position shown in full lines in Figure 8 into the position shown in dotted lines through the use of a withdrawable key 46.

In order that the bolt 3 may be locked against withdrawal from the inside of the car, I connect the outer end of the strip 13 to a strap 47

which extends to an actuatable handle provided upon the inside of the door, of the usual type. The strap 47 is slidably connected to the strip 13 through the medium of a pin 48 which projects outwardly from the strip 13 into the slot 49 in the end portion of the strap 47. The strip 13 carries a pivotally mounted U-shaped catch member 50 mounted upon a pin 51 positioned upon the strip 13 in the vicinity of the end of the slot 14, and such U-shaped member is also pivotally connected to the end of the strap 47 so that in normal actuation of the lock from the outside, the assembly of the strip 13, strap 47 and member 50 all move relatively to the pin 15 projecting through the slot 14 in the strip.

When the bolt 3 is in the outermost or locked position, as illustrated in Figure 3, the U-shaped member 50 is so positioned as to have its hook portion above the pin 15, and if it is desired to lock the door from the inside, the handle upon the inside of the door (not shown) is actuated to move the strap 47 within the limits of the length of the slot 49 whereby such movement will hook the U-shaped member 50 around the head of the pin 14, as illustrated in dotted lines in Figure 3. It will thus be appreciated that irrespective of any actuation of the lock from the outside that the bolt and its strip 13 cannot be moved inwardly due to the engagement of the member 50, carried upon the strip 13, with the stationary stud 15. To unlock the door from the inside, it is only necessary to move the inside handle so that it exerts a pull upon the strap 47 and in turn a retracting pull upon the strip 13 and bolt 3 whereby the bolt is retracted into the lock, when the door can be opened.

To open the door when the lock bolt is retracted, I furnish a resilient element which engages the door under compression when the door is closed, and when the lock bolt is retracted to free the door, such resilient element kicks the door open. In the drawing the up-turned end portion 52 of the plate 1 is formed with a lug 53 which protrudes from the edge of the door and is receivable within a transverse recess 54 in the door jamb 55. The door jamb is also formed with a bolt receiving recess 56 above the recess 54. The transverse recess 54 has a slot 57 in the bottom thereof through which a lug 58 protrudes. The lug is carried upon a slidable cap 59 movable along the length of the slot 57 against a spring 60. When the door is being closed, the lug 53 comes into contact with the lug 58, and compresses the spring 60 so that when the door lock is disengaged to permit the door to be opened, the lug 58 pushing against the door lug 53 under the influence of the spring 60, kicks the door open.

When the door is open, the lock is in the position shown in Figure 1, that is, with the lock bolt 3 retracted and the plunger 4 protruding under a slight compression of the spring 11 tending to move the rod 9 and attached plunger 4 outwardly. The press button with its stop bar 30 is also in the outermost position, as illustrated in Figures 5 and 8. When the door is swung towards the door jamb 55 in being closed, the chamfered face 5 of the plunger 4 engages the edge of the jamb and as the door is being moved inwardly into the closed position, the lock mechanism assumes the position as shown in Figure 2. From this figure it will be seen that as the plunger 4 is moved inwardly its rod 9 is also moved inwardly further compressing the spring 11. In conjunction with the inward movement of the plunger 4

and rod 9, the slide block 6 also is moved inwardly through the engagement of the stop bar 30 therewith. The stop bar 30 is carried by the plunger 4 and movable therewith.

5 The slide block 6 is engaged by the lower end of the lever 16, so that through its inward movement the lever 16 is swung in a clockwise direction and thus compresses both the springs 61 and 62. In this movement the lever 25 also moves 10 under the spring pressures and assumes a position substantially as shown in Figure 2. During the closing movement of the door, the bolt 3 and its strip 13 carrying the upper end of the lever 16 are not free to move as the outer end of the bolt 15 3 is pressing against the side of the jamb and cannot be shot until the bolt registers with the bolt receiving recess 56 in the door jamb. When the door is being closed, the compressed springs 61 and 62 are tending to shoot the bolt 3.

20 When the door is fully closed the lock assumes the position shown in Figure 3, that is, with the bolt 3 shot into the bolt receiving recess 56, and the side of the lever 16 again resting against the fulcrumed edge 21 of the lug 20. It will be readily apparent that as soon as the bolt 3 registered with the bolt receiving recess that such bolt was urged outwardly under the combined pressures of the springs 61 and 62 bearing against the lever 16 which is attached to the strip 13.

30 When it is desired to open the door from the outside, the press button or cylinder 33 is pressed inwardly, and such inward movement upon the stud 37 causes the stop bar 30 to be moved inwardly into the slot 29 in the plunger 4, thus sliding it from out of contact with the end of the block 6. Immediately the stop bar 30 is depressed into the slot 29 out of contact with the block 6, such block is free to slide across the face of the plunger 4, as illustrated in Figures 4 and 6, under 35 the compression of the spring 62 engaging the lower end of the lever 16 which in turn engages the end of the block 6. Such movements of the block 6 and lever 16 about the fulcrum point 20 cause the upper end of the lever 16 to be swung 40 in a counter-clockwise direction, thus retracting the strip 13 and bolt 3 from the recess 56. As soon as this occurs the door is free to open and the compression of the spring 60 in the door jamb acting against the lug 58 kicks the door 45 open. When the door is opened to a point beyond the door jamb, the plunger 4 is free to be pushed outwardly under the influence of the compressed spring 11 acting against the rod 9 which is attached to the plunger 4, so that the plunger 4 is 50 moved outwardly into the position illustrated in Figure 1 wherein the locking bar 30 is free to swing upwardly from its slot 29 under the influence of the spring 40 surrounding the stud 37 and thus re-engage the end of the block 6, whereby 55 the lock mechanism is again in the position as illustrated in Figure 1.

From the foregoing description it will be seen that I utilize the inward swinging movement of the door relatively to the door jamb to compress 60 the spring mechanism which shoots the door bolt and that, although relatively strong bolt springs are used, the compression of such springs through the engagement of the plunger 4 with the door jamb is quite imperceptible in closing the door. 65 As the release of the spring tensions is achieved by what might be described as a trigger mechanism, provided by the stop bar 30 disengageably retaining the spring held moving block 6, the pressure required to move the press button inwardly to disengage the locking bar 30 is only 70 75

very slight. When it is desired to lock the door, the bolt 45 is swung into the position illustrated in dotted lines in Figure 8 by the actuation of the key 46 so that its engagement with the top of the stud 37 prevents the cylinder 33 being pushed inwardly to open the door. Although I have shown a particular embodiment of my invention, it is to be understood that I can make any such changes and alterations as I may from time to time deem necessary without departing from the 10 spirit of my invention as set forth in the appended claims.

What I claim as my invention is:

1. In a door lock, a bolt normally in the retracted position when the door is open, a plunger 15 protruding from the lock when the door is open and positioned to engage and be pushed inwardly by the door jamb as the door is being closed, a lever swingable with and extending between the plunger and the bolt and having one end movable with the plunger and the other end movable with the bolt, a spring bearing against the lever intermediately of its length and compressible against the lever under the lever's movement in conjunction with the inward movement of the 20 plunger, said compressed spring swinging the lever to shoot the bolt when the bolt registers with its bolt receiving orifice in the door jamb, a second spring bearing against the end of the 25 lever which is movable with the plunger, said spring being under compression when the lever has been swung to shoot the bolt, a fulcrum against which the lever bears when the bolt is in the shot position, a releasable element retaining the end of the lever against which the second 30 compressed spring bears, and means operable from the outside of the door for releasing the element from out of retaining engagement with the lever to permit the lever to swing about the fulcrum under the influence of the second spring 35 and retract the bolt.

2. In a door lock, a bolt normally in the retracted position when the door is open, a plunger protruding from the lock when the door is open and positioned to engage and be pushed inwardly 45 by the door jamb as the door is being closed, a lever swingable with and extending between the plunger and the bolt and having one end movable with the plunger and the other end movable with the bolt, a spring bearing against the lever intermediately of its length and compressible against the lever under the lever's movement in conjunction with the inward movement of the plunger, said compressed spring swinging the lever to shoot the bolt when the bolt registers 50 with its bolt receiving orifice in the door jamb, a second spring bearing against the end of the lever which is movable with the plunger, said spring being under compression when the lever has been swung to shoot the bolt, a lever swinging and spring compressing member movable in conjunction with the plunger, an element movable into and out of coupling relationship between the plunger and the lever swinging and spring compressing member, and a member manually operable from the outside of the door to move said element out of coupling relationship between the plunger and the lever to permit the lever to swing under the influence of the second spring and retract the bolt.

3. In a door lock, a bolt normally in the retracted position when the door is open, a plunger protruding from the lock when the door is open and positioned to engage and be pushed inwardly by the door jamb as the door is being closed,

a lever swingable with and extending between the plunger and the bolt and having one end movable with the plunger and the other end movable with the bolt, a fulcrum positioned intermediately of the length of the lever and against which the lever rests when either the bolt or the plunger are protruding, a pair of springs compressed by the inward movement of the plunger in its engagement with the door jamb and tending to shoot the bolt, the inward movement of the plunger moving the lever away from its fulcrum, one of said springs swinging the lever towards the fulcrum to shoot the bolt when the bolt registers with its bolt receiving orifice in the door jamb, the shooting of the bolt returning the lever into contact with the fulcrum, the second spring remaining in compression and tending to swing the lever about its fulcrum and retract the bolt, and a member manually actuatable from the outside of the door to release the lever to swing about its fulcrum under the influence of the second spring and retract the bolt.

4. In a door lock, a bolt normally in the retracted position when the door is open, a plunger protruding from the lock when the door is open and positioned to engage and be pushed inwardly by the door jamb as the door is being closed, a lever swingable with and extending between the plunger and the bolt and having one end movable with the plunger and the other end movable with the bolt, a fulcrum positioned intermediately of the length of the lever and against which the lever rests when either the bolt or the plunger are protruding, a pair of springs compressed by the inward movement of the plunger in its engagement with the door jamb and tending to shoot the bolt, the inward movement of the plunger moving the lever away from its fulcrum, one of said springs swinging the lever towards the fulcrum to shoot the bolt when the bolt registers with its bolt receiving orifice in the door jamb, the shooting of the bolt returning the lever into contact with the fulcrum, the second spring remaining in compression and tending to swing the lever about its fulcrum and retract the bolt, a lever swinging and spring compressing member movable in conjunction with the plunger, an element movable into and out of coupling relationship between the plunger and the lever swinging and spring compressing member, and a member manually operable from the outside of the door to move said element out of coupling relationship between the plunger and the lever to permit the lever to swing and retract the bolt.

5. In a door lock, a bolt normally in the retracted position when the door is open, a plunger protruding from the lock when the door is open and positioned to engage and be pushed inwardly by the door jamb as the door is being closed, a lever swingable with and extending between the plunger and the bolt and having one end movable with the plunger and the other end movable with the bolt, a fulcrum positioned intermediately of the length of the lever and against which the lever rests when either the bolt or the plunger are protruding, a pair of springs compressed by the inward movement of the plunger in its engagement with the door jamb and tending to shoot the bolt, the inward movement of the plunger moving the lever away from its fulcrum, one of said springs swinging the lever towards the fulcrum to shoot the bolt when the bolt registers with its bolt receiving orifice in the door jamb, the shooting of the bolt returning the lever into contact with the fulcrum, the second spring

remaining in compression and tending to swing the lever about its fulcrum and retract the bolt, a trigger mechanism normally retaining the spring urged bolt in the protruding position when the door is closed, and a press button carried on the outer face of the door and adapted upon being pushed inwardly to release the trigger mechanism and permit the lever to swing and retract the bolt.

6. In a door lock, a bolt normally in the retracted position when the door is open, a plunger protruding from the lock when the door is open and positioned to engage and be pushed inwardly by the door jamb as the door is being closed, a lever swingable with and extending between the plunger and the bolt and having one end movable with the plunger and the other end movable with the bolt, a fulcrum positioned intermediately of the length of the lever and against which the lever rests when either the bolt or the plunger are protruding, a pair of springs acting against one side of the lever, a second lever pivoted intermediately of its length and against the opposite end portions of which the springs bear so that the compression force of one spring is transmitted to the other through the second lever, said springs being compressed by the inward movement of the plunger in its engagement with the door jamb and tending to shoot the bolt, the inward movement of the plunger moving the lever away from its fulcrum to shoot the bolt when the bolt registers with its bolt receiving orifice in the door jamb, the shooting of the bolt returning the lever into contact with the fulcrum wherein both of said springs remain in compression, the first spring urging the bolt outwardly and the second spring tending to urge the plunger outwardly and retract the bolt, a lever swinging and spring compressing member movable in conjunction with the plunger, an element movable into and out of coupling relationship between the plunger and the lever swinging and spring compressing member, and a member manually operable from the outside of the door to move said element out of coupling relationship between the plunger and the lever to permit the lever to swing and retract the bolt.

7. In a door lock, a bolt normally in the retracted position when the door is open, a plunger protruding from the lock when the door is open and positioned to engage and be pushed inwardly by the door jamb as the door is being closed, a lever swingable with and extending between the plunger and the bolt and having one end movable with the plunger and the other end movable with the bolt, a fulcrum positioned intermediately of the length of the lever and against which the lever rests when either the bolt or the plunger are protruding, a pair of springs acting against one side of the lever, a second lever pivoted intermediately of its length and against the opposite end portions of which the springs bear so that the compression force of one spring is transmitted to the other through the second lever, said springs being compressed by the inward movement of the plunger in its engagement with the door jamb and tending to shoot the bolt, the inward movement of the plunger moving the lever away from its fulcrum to shoot the bolt when the bolt registers with its bolt receiving orifice in the door jamb, the shooting of the bolt returning the lever into contact with the fulcrum wherein both of said springs remain in compression, the first spring urging the bolt outwardly and the second spring tend-

ing to urge the plunger outwardly and retract the bolt, a trigger mechanism normally retaining the second spring against expansion and retraction of the bolt when the door is closed, and 5 a press button carried upon the outer face of the door and adapted upon being pushed inwardly to release the trigger mechanism for the retraction of the bolt.

8. In a door lock, a bolt normally in the retracted position when the door is open, a plunger protruding from the lock when the door is open and positioned to engage and be pushed inwardly by the door jamb as the door is being closed, a lever swingable with and extending between the plunger and the bolt and having one 10 end movable with the plunger and the other end movable with the bolt, a fulcrum positioned intermediately of the length of the lever and against which the lever rests when either the bolt or the plunger are protruding, a pair of springs acting against one side of the lever, a second lever pivoted intermediately of its length and against the opposite end portions of which the springs bear so that the compression force of one spring is 15 transmitted to the other through the second lever, said springs being compressed by the inward movement of the plunger in its engagement with the door jamb and tending to shoot the bolt, the inward movement of the plunger moving the lever away from its fulcrum to shoot the bolt when the bolt registers with its bolt receiving orifice in the door jamb, the shooting of the bolt returning the lever into contact with the fulcrum wherein both of said springs remain in 20 compression, the first spring urging the bolt outwardly and the second spring tending to urge the plunger outwardly and retract the bolt, a 25 slidable block interposed between the inner end of the plunger and one end of the first lever and

movable in conjunction with the plunger against the lever, a projection on the block overlapping the plunger, a depressible member carried by the plunger and engaging the projection to form a releasable coupling relationship between the plunger and the block, and a press button carried upon the outer face of the door and operably connected to the depressible member and adapted upon being pushed inwardly to depress the depressible member from out of contact with the block projection and release the compression on the second spring to retract the bolt.

9. In a door lock, a bolt assembly normally in the retracted position when the door is open, a plunger protruding from the lock when the door is open and positioned to engage and be pushed inwardly by the door jamb as the door is being closed, a spring element to shoot the bolt and retain it in its shot position compressible by the movement of the plunger into the lock, a stud 15 member contained within the door lock, a hook member pivotally mounted upon the bolt assembly and positioned in proximity to the stud when the bolt is in the shot position, and a manually operable connection extending from the hook to 20 the inside of the door whereby such hook can be moved into a position engaging the stud to retain the bolt against retractive movement, a second spring element also compressible by the movement of the plunger into the lock and tending to 25 retract the bolt, a movable member normally retaining the bolt against retraction by the second spring, and means operable from the outside of the door to actuate the movable member from out of the bolt retaining position whereby the second spring moves the bolt into the 30 retracted position when the hook member is out of engagement with the stud.

ROBERT BUCHANAN McFARLANE.
